POWER CLOTHES WRINGER

Filed June 14, 1928

UNITED STATES PATENT OFFICE

VINCENT G. APPLE, OF DAYTON, OHIO

POWER CLOTHES WRINGER

Application filed June 14, 1928. Serial No. 285,370.

My invention relates principally to that type of clothes wringer having two rolls between which the wet clothes are passed to free the water therefrom, the rolls being driven 5 from a power source, the mechanism including means for starting, stopping or reversing the rotation of the wringer rolls at will.

One of the objects of my invention is to provide a wringer of simple construction 10 having the least number of parts consistent with simplicity and convenience in operation.

Another object of my invention is to provide a wringer which insures the maximum of safety from injury to the operator.

15 Other objects will become apparent to those skilled in the art as the invention is described in detail and reference is made to the drawings, wherein—

Fig. 1 is a plan view of the wringer with such portions broken away as are indicated by lines 1—1 and 1'—1' Fig. 3.

Fig. 2 is an end view.

Fig. 3 is a front elevation with the front half of the frame removed.

25 Figs. 4, 5 and 6 have a portion of the frame removed to show some of the features in detail.

Fig. 7 is a plan view of a washing machine 30 which is equipped with my improved wringer associated with a standard two compartment laundry tray.

Similar numerals refer to similar parts thruout the several views.

Referring to the drawings a frame 10 35 has as a part thereof guides 11 within which plates 12 may have a limited vertical movement. Plates 12 in turn serve as guides for bearings 13 and 14 which may have a limited vertical movement in said plates; bearings 13

40 and 14 in turn supporting wringer rolls 15 and 16. A semi-elliptic spring 17 in the upper part of the frame, by pressure on bearings 13, thru links 18, maintains resilient pressure between the rolls. A regulating screw 19 45 passing thru nut 20 may be adjusted to vary the degree of pressure exerted by the spring.

A square shaft 21 rounded at portions thereof passes thru and beyond the length of the frame 10 and has a control handle 22 50 at each end and at rounded portions 23 has

bearings in the frame to permit rotation. Flanged hubs 24 and 25 mounted on a square portion of shaft 21 have studs 26 carrying rollers 27, which may bear on the upper edge 28 of the opening in plates 12. It may be 55 seen that when control handles 22 are positioned to extend vertically from the frame, plates 12 will be lowered and as the lower roll bearings 14 rest upon said plates the lower rolls 16 will be dropped a considerable 60 distance away from the upper roll 15, the upper roll 15 being prevented from following downward to any great extent by the contact of spring 17 with rounded portions 29 of shaft 21. When however, control han- 65 dle 22 is drawn downward in either direction from the vertical position to a horizontal position rollers 27 acting against the edges 28 of plates 12 raise plate 12 and again bring wringer rolls 15 and 16 together under re- 70 sistant pressure of spring 17 without having disturbed the adjustment of regulating screw 19. Light springs 30 may be placed between bearings 13 and 14 to assist in forcing the rolls 15 and 16 apart when control handles 75 22 are raised to their vertical position.

Mounted near the end of rolls 15 and 16 are gears 31 and 32 which preferably mesh so that one roll may drive the other but which need not necessarily do so to come within 80 the scope of my invention as one roll may drive the other by friction if desired. For illustrative purposes only I herein show a roll-reversing means which consists of a member 33 mounted to rock on stud 34 and carrying idler gears 35 and 36 on studs 37 and 38. A shaft 39 connected to the power source carries gear 40 which is always in mesh with idler gears 35 and 36. 85

Extending from one side of flanged hub 25 is a stud 41 and extending from one side of member 33 is another stud 42. Connecting the studs 41 and 42 is a link 43. Stud 41 is so placed in flanged hub 25 that when control handles 22 are moved to extend vertical- 90 ly from the frame, stud 41 thru link 43 and stud 42 draws member 33 to a position which holds idler gears 35 and 36 entirely out of control with roll gears 31 and 32. When how- 95 ever, control handles 22 are moved to hori- 100

zontal positions member 33 moves idler gears 35 and 36 to such position as will contact either the upper roll gear 31 or the lower roll gear 32 to revolve the rolls in either one or the other direction depending upon which horizontal position of the control handles 22 is selected.

Mounted on square portions of control shaft 21 are eccentrics 44. A drain pan 45 below the wringer frame is hinged on lugs 46. Studs 47 in the drain pan are connected to eccentrics 44 by links 48. Eccentrics 44 are so placed on control shaft 21 that when control handles 22 are brought to either horizontal position the pan will slope in one or the other direction as required.

From the foregoing description it is apparent that when a control handle of my improved wringer is brought to a vertical position the rolls are spread widely apart and are freed from the source of power and from each other so that either may be freely turned by hand in its bearings and the adjustment of the roll tensions is undisturbed; when the control handle is brought to a horizontal position toward the operator the rolls are brought together under normal tension, are connected to the source of power and made to revolve to wring clothes away from the operator and the drain pan is slanted to return the water wrung from the clothes toward the operator and this action may be had by the operator from either side of the wringer, and as there is a control handle at each end of the wringer it may be conveniently controlled by either the right or left hand as desired, and when my wringer is mounted on a column to swing thereabout in a horizontal plane to several positions as is common practice it will be found that one or the other control handle is always within easy reach of the operator in any of the several positions.

The advantages of my improved construction over common practice are obvious. In a power wringer as ordinarily made there is a single control handle by means of which the rolls may be stopped or rotated in either direction. The operator of such a wringer must always remember to manually slant his drain pan in a proper direction when starting to wring. If as frequently happens in ordinary practice an article of clothing being wrung out inadvertently wraps around one of the rolls or anything else occurs to choke the rolls and overcome the source of power the operator may reverse the wringer if the source of power is sufficient to reverse the rolls against the choking action. This failing he may strike a catch usually provided on most such wringers which release the tension screw and breaks the rolls apart. But breaking the rolls apart still does not disconnect such a wringer from the source of power and the operator must then still reach the control handle and stop or reverse the

rolls, after which he must reset his catch and readjust the tension of the rolls.

In order to more clearly show my improved wringer compared with ordinary wringers I show in Fig. 7 a standard two compartment laundry tray 55 and a washing machine 56 of the swinging wringer type equipped with my improved wringer.

It is common practice to so place the washing machine with reference to the laundry tray that the wringer may be swung to either of the four positions shown which I broadly designate as positions 48, 49, 50, and 51. The operator stands in position 52 when the wringer is in position 48 or 51. He stands in position 53 when the wringer is in position 49. He stands in position 54 when the wringer is in position 50. Ease of access to the control handles 22 is hereby obvious. However, when the operator of an ordinary wringer is standing in position 54 with the wringer in position 50 and necessity for quickly reversing the rolls occurs he may find that the reversing handle is too far away to be reached from his position as it is on many machines so placed as to then be in a position as at 57 several feet removed from his standing position.

While I prefer that my improved wringer which I have herein shown and described be driven by a power unit such as I show in my co-pending application Serial No. 285,369, filed June 14th, 1928 it may be used in conjunction with any driving means desired and while I have referred to a number of changes which may be made in the details of the wringer it is understood that other changes in the structure may be made insofar as they are not limited by the prior art and do not depart from the spirit of the invention the scope of which I aim to cover in the following wherein I claim—

1. In a wringer for a power washer, a frame, two roll shafts rotatably supported in bearings carried by said frame, a gear on each said roll shaft, a unidirectional power shaft, a gear on said power shaft, two idler gears and manual means carrying the two said idler gears, adapted to be shifted to three positions, the one position to insert one idler gear into mesh between the power shaft gear and the one roll gear, another position to insert the other idler gear into mesh between the power shaft gear and the other roll gear, and the third position to withdraw both idler gears from mesh with the roll gears.

2. In a wringer for a power washer, a frame, two roll shafts rotatably supported in bearings carried by said frame, a gear in each said roll shaft, a unidirectional power shaft, a gear on said power shaft, an idler gear bracket having rotative movement about said power shaft, two idler gears rotatably supported on said bracket and in

constant mesh with said power shaft gear, and a manually operable lever adapted to give rotative movement to said bracket to bring the one idler gear into mesh with the one roll shaft gear, to bring the other idler gear into mesh with the other roll shaft gear or to remove both idler gears from mesh with both roll shaft gears.

3. In a wringer for a power washer, two roll shaft gears in mesh, a spaced apart unidirectional power shaft gear, an idler gear bracket adapted for part rotation about said power shaft, two idler gears carried by said bracket, in constant mesh with said power shaft gear, one positioned to be swung into mesh with the upper roll gear upon rotation of the bracket in one direction, and the other positioned to be swung into mesh with the lower roll gear upon rotation of the bracket in the other direction, a central shaft, a stud eccentrically secured thereto and operable thereabout, and a link connecting said stud to said idler gear bracket as described.

4. In a power wringer having two rolls and unidirectional power means connectible to said rolls for driving said rolls in either direction, the combination of means for operatively connecting the upper roll to the power means, means for operatively connecting the lower roll to the power means, and a manually operable lever movable in the one direction to render the first said connecting means operative and the second inoperative, and movable in the other direction to render the second said connecting means operative and the first inoperative.

5. In a power wringer having two rolls and unidirectional power means connectible to said rolls for driving said rolls in either direction, the combination of means for operatively connecting the upper roll to the power means, means for operatively connecting the lower roll to the power means, and a manually operable lever movable in the one direction to render the first said connecting means operative and the second inoperative, and movable in the other direction to render the second said connecting means operative and the first inoperative, and movable to a central position to render both said connecting means inoperative.

6. In a clothes wringer having a frame with two horizontally disposed axially parallel rolls vertically movable in said frame and situated one above the other, the combination of a spring means for forcing the upper roll downwardly, stops in said frame to limit downward movement of said upper roll, and a manually operable lever for moving said lower roll downwardly and away from said upper roll after said upper roll is restrained from further downward movement by said stops.

7. In a power wringer having a frame, two axially parallel rolls vertically movable in

said frame one situated above the other, and a unidirectional power means for rotating said rolls, the combination of spring means for moving the upper roll downwardly, stops in said frame to limit said downward movement, mechanism for moving the lower roll downwardly and away from the upper roll, mechanism for operatively connecting the one roll to the power means, mechanism for operatively connecting the other roll to the power means, and mechanism manually movable in one direction for simultaneously raising the lower roll against the upper and operatively connecting the upper roll to the power means, manually movable in the other direction for simultaneously raising the lower roll against the upper and operatively connecting the lower roll to the power means and manually movable to a central position to move the lower roll downwardly away from the upper and disconnect both rolls from the power means.

8. In a power clothes wringer having a frame, two horizontally disposed axially parallel rolls one above the other in said frame, a tiltable drain pan supported on said frame below said rolls and power means to rotate said rolls, the combination of power transmitting mechanism to connect said power means to said rolls to wring forward or backward, a linkage operable to tilt said drain pan forward or backward, and a single manually operable lever connected to said transmitting mechanism and said linkage movable in one direction to simultaneously tilt the drain pan backward and connect the power to wring forward, and movable in the other direction to simultaneously tilt the drain forward and connect the power to wring backward.

9. In a power clothes wringer having two horizontally disposed axially parallel rolls one above the other, power means for operating said rolls, a tiltable drain pan below said rolls, and a lever manually operable in one direction to wring forwardly, in the other direction to wring backwardly, and to a central position to stop the rolls, the combination of linkage connecting said lever to the lower roll adapted to move said roll downwardly and widely apart from the upper roll when said lever is manually operated to the said central position, and linkage connecting said lever to said drain pan adapted to tilt said pan backwardly when said lever is operated to wring forwardly and to tilt said pan forwardly when said lever is operated to wring backwardly.

In testimony whereof I hereunto set my hand.

VINCENT G. APPLE.
